(57) **CLAIM**

The ornamental design for a food storage container, as shown and described.

DESCRIPTION

FIG. 1 is a top, front, left perspective view of a food storage container showing our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1;

FIG. 8 is a top, rear, right perspective view of FIG. 1; and,

FIG. 9 is an exploded perspective view of FIG. 1.

The broken lines in the drawings depict portions of the food storage container that form no part of the claimed design.

1 Claim, 9 Drawing Sheets
